UNITED STATES PATENT OFFICE.

HENRY H. DILLE AND ELWOOD W. McGUIRE, OF RICHMOND, INDIANA,
ASSIGNORS TO THE DILLE & McGUIRE MANUFACTURING COMPANY,
OF SAME PLACE.

APPARATUS FOR MEASURING AND CUTTING FABRICS.

SPECIFICATION forming part of Letters Patent No. 376,642, dated January 17, 1888.

Application filed May 1, 1886. Serial No. 200,867. (No model.)

To all whom it may concern:

Be it known that we, HENRY H. DILLE and ELWOOD W. McGUIRE, of Richmond, in the county of Wayne, and in the State of Indiana, have invented certain new and useful Improvements in Apparatus for Measuring and Cutting Fabrics; and we do hereby declare that the following is a full, clear, and exact description thereof, reference being had to the accompanying drawings, in which—

Figure 1 shows a view in perspective of our machine or apparatus; Fig. 2, a detail view in side elevation of the measuring device and the part of the machine-frame for holding the same, and Fig. 3 a detail perspective view of the measuring device and the means for holding the same separated.

Letters of like name and kind refer to like parts in each of the figures.

20 The object of our invention is to provide a machine or apparatus for holding, measuring, and cutting wire cloth, architects' paper, window-shade material, &c.; and to this end our invention consists in the machine or apparatus and in the parts thereof, constructed, arranged, and combined as hereinafter specified.

In the drawings, A designates the frame of our machine, which can be of any desired shape, but which we prefer to make of two similarly-shaped ends, A' A', each consisting of an annular part, a, resting on two standards or feet, a' a', and having within and made in one piece with the annular part the star-shaped frame or piece a². The corresponding feet or standards, a' a', on the opposite ends of the frame are connected by bars or beams A² A². In bearings on the upper portions of the frame ends are journaled the opposite ends of the shaft B, carrying the two heads C C, fixed on it just inside the frame ends. Such heads are, like the reel-heads shown and described in my application Serial No. 197,745, now pending, provided with series of opposite sockets, c c, in which sockets are supported the opposite ends of rods or rollers B B, for receiving and carrying separate rolls or bolts of the material to be handled. To facilitate the insertion and removal of the rod ends in their sockets, such

sockets are, like those described and shown in 50 our other application referred to, made larger than the rod ends, and in their outer sides or bottoms are provided with central openings of sufficient size to admit the passage of the rod ends when the rod has been raised to bring 55 such ends in central position within the sockets. With such construction, when the opposite ends of a rod have been properly inserted in its sockets, the portion of the socket ends or bottoms around the central openings therein 60 will normally engage the rod ends and prevent such rod from moving endwise, so as to disengage either of its ends from its socket.

To prevent a roll of material from coming 65 unwound accidentally after it has been placed on its respective rod, we prefer to use the plates D D, constructed as fully set forth in our other application referred to, and engaging the roll ends. To forwardly-extending brackets a³ a³ on the front of the frame A' A' are attached 70 the opposite ends of the bar E, parallel with the axis of rotation of the connected heads C C, and preferably angular in cross-section. On one of the frame ends, just above the bar E, is a socket, F, adapted to receive the measure G, preferably of the well-known kind, having a measuring-tape and a retracting or winding spring mechanism for winding back the measuring-tape when it has been pulled out 75 and released.

The ordinary spring-stop device, indicated at 80 g, for engaging and disengaging the spring-winding mechanism can be used or not, as desired. Without it the tape would of course be wound back directly as soon as its end was 85 released.

The socket, as shown, fits the disk-shaped case of the measure closely, and is closed on its inner side, so as to afford bearing for the inner side of the measure-case. On its front side 90 the socket is provided with an opening, H, to admit the outward passage of the measuring-tape close to the top of the bar E.

When the measure G has been properly placed in its socket, it is fastened there by the 95 set-screw g', screwed down to engage the measure-casing, as indicated in the drawings.

The bar E, over which the goods to be meas-

ured and cut are drawn from the roll, forms a guide for the movable cutter I, adapted to cut the goods off on a line parallel with the bar. Such cutter can be of any of the forms 5 shown and described in our other application referred to. In the drawings of the present case we show only one form, which consists of the stationary blade K, fixed to a sleeve, K', sliding on the bar, and a pivoted and handled 15 knife, K", operating in conjunction with such fixed blade with a shearing action.

The operation of our machine or apparatus is briefly as follows: Rolls of material of the various kinds or dimensions having been 20 placed on the different rods of the reel-like carrier, when a piece from any one of the rolls is desired, the carrier is rotated to bring such roll down to the bar E. A spring-stop, for locking the carrier when it has been rotated 25 to bring the desired roll into position, can be employed. Such a stop is indicated at L, but need not be specifically described or shown, as it is similar in construction and operation to the one described and shown in our other 30 application. The desired roll having been brought into position close to bar E, and of course parallel to it, the end of the material on the roll and the end of the measuring-tape are pulled forward together over the bar until the 35 graduations on the tape indicate the amount of fabric in feet and inches desired. The tape is then released, and the fabric resting on the bar E is cut close to the edge thereof by moving and operating the cutter along the bar.

Where no catch or stop is used for the spring rewinding mechanism for the measuring-tape, such tape will, as soon as released, be immediately wound up out of the way, and be ready 40 for use for another measuring. Where the catch or stop is used, but a touch is necessary to cause the tape to be recoiled or rewound again.

Whether rewinding immediately or not, the 45 tape is, when dropped, after the measuring of the fabric, out of the way of the cutter entirely.

If a piece is desired off of another roll, the 50 revolving roll or carrier is unlocked and rotated to bring such other roll into position close to bar E, and automatically locked again

by the spring-stop. Such locking-stop is not at all necessary, and can be dispensed with, if desired.

Having thus described our invention, what we claim is—

1. A machine for holding and measuring fabrics having the guide over which the goods are drawn, a tape-measure arranged close to the guide, so that the tape, as drawn out therefrom, passes close to and at right angles to the 60 guide, and the cutter moving along the guide, substantially as and for the purpose specified.
2. The machine having means for holding a roll of goods so as to allow of its being unwound, a guide-bar over which the goods pass 65 as unwound, a tape-measure arranged so that its tape can be drawn over the guide-bar close to the goods and at right angles to the guide-bar, and a cutter moving along said bar, substantially as and for the purpose shown.
3. A machine for holding, measuring, and cutting fabrics, having a guide for the cutter, a cutter moving along the guide, a tape-measure at one end of such guide, and a revolving carrier adapted to receive and hold several 70 rolls of goods, so that such rolls can be brought successively near and parallel to the guide, substantially as and for the purpose set forth.
4. In combination with bar E, the tape-measure socket just above the same, the tape-measure in the socket, and the set-screw engaging the case of the measure, substantially as and for the purpose set forth.
5. A machine for holding, measuring, and cutting goods, having the revolving heads and 85 rods carried thereby for receiving and holding the goods, the cutter-guide arranged parallel to the roll-receiving rods, the cutter movable along such guide, and the tape-measure situated close to the guide, substantially as and 90 for the purpose shown.

In testimony that we claim the foregoing we have hereunto set our hands this 6th day of March, 1886.

H. H. DILLE.
ELWOOD W. McGUIRE.
